UNITED STATES PATENT OFFICE.

CHARLES R. WHITE, OF PORTLAND, MAINE.

DESIGN FOR A WASH-BRUSH BODY.

SPECIFICATION forming part of Design No. 17,230, dated March 29, 1887.

Application filed February 7, 1887. Serial No. 226,870. Term of patent 3½ years.

To all whom it may concern:

Be it known that I, CHARLES R. WHITE, a citizen of the United States, residing at Portland, in the county of Cumberland and State of Maine, have produced a new and original Design for Wash-Brushes; and I do hereby declare the following to be a full, clear, and exact description of the invention, such as will enable others skilled in the art to which it applies to make and use the same.

My invention consists in the peculiar shape or configuration of a "wash-brush." These brushes are without handles, but are provided with holes for the insertion of handles.

15 My new design consists of a brush-body having on each end a reversed curve extending from a point each side of center of the top down to the end at or near the ledge or shoulder B. This curve has in it a central longitudinal groove extending its entire length.

20 My invention is illustrated in the accompanying drawings, in which Figure 1 represents a perspective view of a wash-brush body embodying my design. Fig. 2 represents a cross-25 section near the central portion.

The brush-body has formed on its upper part and on each side of the center reversed curves, which extend obliquely downward to a point at or near the ledge or shoulder B.

25 A represents a groove which is cut longitudinally in the shoulder formed by the reversed curve spoken of.

I claim—

In a design for a wash-brush, a brush-body the upper portion of which has the configuration of a reversed curve on each side of the center, said curve extending obliquely downward to the end of said body, and having formed therein a central longitudinal groove, and having on each side the base B a ledge or shoulder, as shown and described.

30 In testimony whereof I affix my signature in presence of two witnesses.

CHARLES R. WHITE.
